UNITED STATES PATENT OFFICE.

EMMETT E. MILLER, OF NORFOLK, VIRGINIA.

SCREEN DOOR, WINDOW, OR THE LIKE.

Application filed November 16, 1920. Serial No. 424,398.

To all whom it may concern:

Be it known that I, EMMETT E. MILLER, a citizen of the United States, residing at Norfolk, in the county of Norfolk and State 5 of Virginia, have invented new and useful Improvements in Screen Doors, Windows, or the like, of which the following is a specification.

The object of my present invention is the 10 provision of a simple and extremely strong and durable screen door, window or the like, and one which the section of screen or reticulated material is maintained under tension and in flat state, and which is so constructed that the screen section may be expeditiously and easily removed when worn 15 or broken and replaced by a new screen section without the employment of skilled labor and without the loss of any part other than the worn or broken screen section.

To the attainment of the foregoing, the invention consists in the improvement as hereinafter described and definitely claimed.

In the accompanying drawings, forming 25 part hereof:

Figure 1 is a front elevation showing a screen door constructed in accordance with my invention and with a part broken away.

Figure 2 is a vertical central section of 30 the same.

Figure 3 is an enlarged detail transverse section taken in the plane indicated by the line 3—3 of Figure 1.

Figure 4 is a detail interior elevation 35 showing one corner of the main frame and the auxiliary frame fixed thereto.

Figure 5 is an elevation showing in detail the screen section, the screen frame, and the means comprised in the screen frame 40 whereby the screen section is put under tension and is maintained in a flat and taut state.

Figure 6 is an enlarged detail transverse section showing how the screen section is 45 connected to the side bars of the screen frame.

Figure 7 is an enlarged transverse section taken in the plane indicated by the line 7—7 of Figure 5 and showing a part of the means 50 to put the screen section under tension.

Figure 8 is a detail view of a modification hereinafter explicitly referred to.

Similar numerals designate corresponding parts in Figures 1 to 7 to which reference will first be made.

My novel door includes five major elements, viz; a main frame 1, an auxiliary frame 2 permanently fixed to the main frame, a section 3 of screen or reticulated material, a screen frame 4 and a facing 5. 55 The main frame 1 is preferably, though not necessarily, made of wood, and comprises an end bar 6, and side bars 7. The auxiliary frame 2 is preferably formed of sheet metal and is arranged against and permanently 60 connected to one side of the main frame. The said auxiliary frame 2 is provided with large openings 8 which are surrounded by flanges 9, Figures 2 and 4. Said auxiliary frame is also provided with a keeper flange 70 10 at one end thereof within which is a rest 11, carried by the end wall 12 of the auxiliary frame. It will also be observed by comparison of Figures 1, 2 and 4 that the auxiliary frame 2 is provided at points be- 75

tween the outer corners of the flanges 9 and the corners of the main frame 1 with comparatively shallow diagonal rests 13. At points between the inner transverse flanges 9 the longitudinal flanges 9 are recessed as 80 indicated by 14 and best shown in Figure 2. It will further be noted that bolts 15 are carried by the auxiliary frame 2 and are arranged about the flanges 9 thereof, Figure 2, and that other bolts 16 are carried by 85 the main frame 1. Each of these bolts has an angular head 17 at one end and an exteriorly angular cap nut 18 at its opposite end; the said cap nuts 18 being designed to detachably secure the screen frame 4 and 90 the sheet metal facing 5 to the main frame 1 and the auxiliary frame 2.

The sheet metal facing 5 is apertured to receive the bolts 15 and 16, and from the foregoing it will be apparent that all that is 95 necessary in order to associate the screen frame 4 and the facing 5 with the main frame 1 and the auxiliary frame 2 is to arrange the screen frame 4 against the edges of the flanges 9 and so that the extended end 100

portions of the side bars 20 of the screen frame rest on the rests 13, and then slip one end of the facing 5 under the flange 10 of the auxiliary frame 2 and so that said end rests between the flange 10 and on the rest 11. The screen frame 4 is not apertured. With this done, it being remembered that the facing 5 receives the bolts 15 and 16, the nuts 18 are applied to retain the facing 5 and the screen frame 4 in position in the assembled door. From this it follows that by merely removing the nuts 18 and disassociating the facing 5 and the screen frame 4 from the main frame 1 and the auxiliary frame 2, the screen frame is rendered free to be handled with facility for the removal of a worn or broken screen and the replacing of the same with a fresh screen or screen section as will now be described.

By particular reference to Figures 5, 6 and 7 the screen frame 4 will be understood as comprising the side bars 20, preferably of sheet metal, and cross bars 21. The said cross bars 21 which are also preferably of sheet metal, are fixed to one side bar 20 as indicated by 22 and are arranged loosely in apertures 23 in the other side bar 20. The screen or screen section 3 is connected to the side bars 20 in the manner best shown in Figures 1 and 6—i. e., tongues 24 are struck up from the side bars 20, and the screen section 3 hooked over the said tongues 24. The tongues 24 are directed outwardly, and from this it follows that when the side bars 20 are thrust away from each other the screen section 3 will be placed under considerable tension and will be rendered taut and flat throughout. To accomplish the said thrust in opposite directions of the side bars 20 I provide the toggle lever equipment best shown in Figure 5, each of the toggle levers including a link 30 pivoted at 31 to one cross bar 21, and a link 32 pivoted at 33 to the link 30 and at 34 to one side bar 20. Each of the links 30 is notched at 35, and each link 32 is provided at its inner end with a reduced extension 37 which terminates in an angularly disposed stop portion 38 adapted when the toggle levers are pressed downwardly beyond their centers to seat in the said notches 35. Manifestly when this is done the toggle levers will be locked to maintain the screen section 3 in a stretched or taut state, and there will be no liability of the toggle levers being accidentally unlocked or permitted to flex upwardly. When, however, it is desired to render the screen section 3 loose so that the same may be unhooked from the tongues 24, the toggle levers may be expeditiously and easily flexed upwardly.

It will also be apparent from the foregoing that when the screen frame 4 is in the state shown by full lines in Figure 5, the said screen frame with its screen section 3 is

adapted to be associated with the main frame 1 auxiliary frame 2 and facing 5 in the manner before described.

In the modification shown in Figure 8 the cross bars 21 are altogether omitted from the screen frame 4^a, and each of the toggle levers of the screen frame is made up of links 30^a and 32^a, the link 30^a being pivoted at 31^a to one side bar 20^a and the link 32^a being pivoted at 34^a to the other side bar 20^a. The links 30^a and 32^a are pivoted together and are otherwise similar to the links 30 and 32 of Figure 5. Consequently when the said links 30^a and 32^a are moved downwardly beyond center they will thrust the side bars 20^a in opposite directions and will remain in the positions in which they are placed without liability of casual movement.

I would here have it understood that I prefer the construction shown in Figure 5, though I do not desire to be understood as limiting myself to the same.

It will be apparent from the foregoing that my novel screen door is adapted to last as a whole for an indefinite period of time, it being simply necessary at intervals of time to replace a worn or broken screen section 3 with a fresh screen section, and this as before pointed out may be quickly and easily accomplished without invoking the assistance of skilled labor.

The term door as herein employed is intended to comprehend a door, window or any other device that embodies a screen for the exclusion of flies and other insects.

I would further have it understood that it is entirely within the purview of my invention to form any one of the elements of the screen door of any material that is compatible with the purpose of the said element.

Having described my invention, what I claim and desire to secure by Letters Patent, is:—

1. The combination in a screen door, of a main frame, an auxiliary frame fixed to the main frame and provided with an end flange and with a rest spaced from the inner side of and arranged opposite said flange and also provided with large flanged openings and comparatively shallow rest portions, headed bolts carried by the main frame and the auxiliary frame, a screen frame arranged against said shallow rest portions, a screen carried by the screen frame and resting against the edges of the flanges defining said openings of the auxiliary frame, a facing arranged over the screen and screen frame and receiving the bolts of the main frame and having one end interposed between the said end flange and rest spaced therefrom, bolts extending through the auxiliary frame and the facing, and removable securing means associated with the said bolts at the outer side of the facing.

2. The combination of a screen frame hav-

ing portions one of which is movable laterally toward and from the other, a screen connected to and extending between said portions, and means to thrust the movable portion away from the other portion and to lock it against inward movement to render the screen taut and maintain it in tight and flat state; the connection of the screen to

said portions being effected by outwardly directed tongues on the portions extending through interstices of the screen, whereby when movement of the portions toward each other is permitted the screen may be readily detached from the portions.

In testimony whereof I affix my signature.

EMMETT E. MILLER.
